(57) **CLAIM**

The ornamental design for a body razor, as shown and described.

DESCRIPTION

FIG. 1 is a perspective view of a design according to a first embodiment of the present invention;

FIG. 2 is a left side elevation view of the design according to the first embodiment of the present invention; the right side being a mirror view thereof;

FIG. 3 is a top view of the design according to the first embodiment of the present invention;

FIG. 4 is a bottom view of the design according to the first embodiment of the present invention;

FIG. 5 is a rear elevation view of the design according to the first embodiment of the present invention;

FIG. 6 is a front elevation view of the design according to the first embodiment of the present invention;

FIG. 7 is a perspective view of a design according to a second embodiment of the present invention;

FIG. 8 is a left side elevation view of the design according to the second embodiment of the present invention; the right side being a mirror view thereof;

FIG. 9 is a top view of the design according to the second embodiment of the present invention;

FIG. 10 is a bottom view of the design according to the second embodiment of the present invention;

FIG. 11 is a rear elevation view of the design according to the second embodiment of the present invention; and,

FIG. 12 is a front elevation view of the design according to the second embodiment of the present invention.

The broken lines in the drawings illustrate portions of the article and form no part of the claimed design.
